UNITED STATES PATENT OFFICE.

FRANK ROWLEY, OF WHALEY BRIDGE, ENGLAND.

MANUFACTURE OF TENNIS AND SIMILAR PLAYING-BALLS.

No. 902,330.

Specification of Letters Patent.

Patented Oct. 27, 1908.

Application filed July 15, 1908. Serial No. 443,621.

To all whom it may concern:

Be it known that I, FRANK ROWLEY, a subject of the King of Great Britain, and resident of Whaley Bridge, in the county of Chester, England, have invented certain new and useful Improvements in the Manufacture of Tennis and Similar Playing-Balls, of which the following is a specification.

This invention relates to improvements in tennis and similar playing balls, the object of the improvements being to produce a more durable ball. Hitherto, to attain the same object it has been proposed to cement a restraining cover of fabric to the outside of the interior indiarubber ball and to cement the usual felt outside covering to the fabric. This method has not been a success, probably owing to manufacturing defects.

Now my invention consists principally, in using a layer of indiarubber outside the fabric, said layer being in an unstretched condition while the inner layer and fabric covering are in tension through the inflation of the ball.

On the drawing attached hereunto Figure 1 represents a vertical section through my improved ball, and Fig. 2 a horizontal section with the innermost rubber shell removed, showing the positions of the several layers of materials.

In making the ball, the restraining cover or shell *a* is formed preferably of six or more segments of a spheroid cut from a suitable fabric such as fine canvas indiarubber proofed on both sides, and cut on the bias so that when inflated a true sphere is obtained. The segments of the fabric shell are preferably stitched together with either overlapped or turned in seams, one seam being left unfastened until the indiarubber lining is inserted, when it is stitched up. The indiarubber lining *b* may be first formed as a bladder having a small swelling such as *c* inside through which it can be inflated by means of a needle pointed inflator. The bladder is inserted through the open seam as before stated. The indiarubber lining may however be formed by inserting some indiarubber solution in the fabric shell and closing up the seam. The shell is then rolled round until

the solution is spread over the inside surface to the desired thickness.

The shell *a* may be inflated by the means before described either before the solution is spread over the inside surface or after, the 55 indiarubber swelling *c* which acts as a self closing valve after being punctured, being previously secured in position.

When the shell *a* and lining *b* are complete and inflated to the desired hardness, the outside of the shell *a* is coated with a thin covering *d* of indiarubber which may be applied in any suitable way. For instance, the shell may be coated by painting with indiarubber solution or by cementing thin sheet indiarubber thereto. Over the coating *d* is applied the final or outer covering *e*. This may be of indiarubber compound, of a granulated nature or having a roughened surface, or it may be of any other suitable material. 70 For instance, the ordinary felt covering may be applied to my improved ball.

The canvas shell *a* may be made of two thicknesses of fabric. In this case, the second, or outer thickness or layer is applied 75 when the first or inner one is inflated, the two layers being, preferably, cemented together, the second or outer one either being made in two halves afterwards stitched together when on the shell *a* or built round the latter. The ball is finally finished by curing the indiarubber in a mold in the ordinary way. If the ball is to be covered with felt this is done after curing by preference.

I claim as my invention:

The improved manufacture of tennis and similar playing balls which consists in first forming a restraining shell of shaped segments of indiarubber proofed fabric sewn together, lining this shell internally with indiarubber, inflating the lined shell and coating it externally with indiarubber, while inflated, attaching an outer covering to the ball so formed, and vulcanizing the ball.

In testimony whereof I have hereunto set 95 my hand in the presence of two witnesses.

FRANK ROWLEY.

Witnesses:

CARL BOLLÉ,
WILLIAM JONES.
